UNITED STATES PATENT OFFICE.

ORVILLE E. MURPHY AND SEBURN W. GRAHAM, OF WILSON, OKLAHOMA

ROTARY DEEP-WELL DRILL.

Application filed July 7, 1922. Serial No. 573,290.

To all whom it may concern:

Be it known that we, ORVILLE E. MURPHY and SEBURN W. GRAHAM, citizens of the United States, residing at Wilson, in the county of Carter and State of Oklahoma, have invented certain new and useful Improvements in Rotary Deep-Well Drills, of which the following is a specification.

This invention relates to an improved rotary deep well drill and seeks, as one of its principal objects, to provide a device of this character wherein the cutting blade may, when worn out, be readily detached and a new blade substituted in lieu thereof.

18 The invention has a further object to provide a drill embodying a supporting head or stock and wherein the blade will be removably mounted upon said head so that only the blade need be discarded when worn.

Another object of the invention is to provide a drill wherein the blade will be rigidly clamped upon the head and wherein the blade will not only be held against sidewise movement but will also be held against endwise movement.

And the invention has as a still further object to provide a device wherein the blade may be detached with a minimum of difficulty.

Other and incidental objects will appear hereinafter.

In the drawings:

Figure 1 is a fragmentary side elevation of our improved drill,

Figure 2 is a detail edge elevation of the device,

Figure 3 is a fragmentary vertical sectional view taken medially through the drill,

40 Figure 4 is a transverse sectional view on the line 4—4 of Figure 1, looking in the direction of the arrows,

Figure 5 is a perspective view showing the sections of the head as well as the bit disassembled,

Figure 6 is a side elevation showing a slight modification of the invention,

Figure 7 is a fragmentary vertical sectional view on the line 7—7 of Figure 6, looking in the direction of the arrows, and

Figure 8 is a fragmentary side elevation showing a still further modification.

In carrying the invention into effect, we employ a blade 10 of the fish-tail type. As shown in Figure 3, the upper end of this blade is tapered in transverse vertical sec-

tion, the blade being thickest at its upper terminal. Furthermore, as best brought out in Figure 5, the upper end of the blade, at each side thereof, is formed with a pair of oppositely sloping faces 11 inclining outwardly in opposite directions toward the side edges of the blade, the upper end of the blade being gradually thickened in transverse horizontal section from a point medially thereof toward its side edges. In conjunction with the blade, we employ a supporting stock or head which is split medially into companion sections 12. At its upper end this head is formed with a tapered shank 13, companion portions of which are carried by the sections 12, and formed in the lower end of the head is a medial notch 14 to accommodate the upper end of the blade. The sections 12 thus also carry companion portions of this notch and, as will now be observed, the notch serves to define a pair of coacting jaws 15 at the lower ends of the sections. As shown in Figure 5, each of these jaws is formed with a pair of oppositely sloping inner side faces 16 adapted to engage the side faces 11 of the blade 10 while, as brought out in Figure 3, the side faces 16 are also tilted vertically so that said faces will thus lie flat against the faces 11, the faces of the jaws converging toward the lower ends of the jaws. In other words, the notch 14 is tapered in transverse vertical section to snugly accommodate the upper end of the blade. Formed through the sections 12 of the head to straddle the blade are water passages 17 and threaded upon the shank 13 of the head is a tubular collar 18 for connecting the drill with a drill stem. As will be seen, this collar will serve to bind the sections 12 of the head together and rigidly clamp the blade 10 between the jaws 15 of the head. Thus, the faces 16 of said jaws will coact with the faces 11 for rigidly holding the blade against sidewise movement and will also coact with the faces 11 for rigidly holding the blade against endwise movement. The blade will thus be securely fixed upon the head. However, by unthreading the collar from the shank 13, the sections of the head may be freely separated for releasing the blade when, of course, the blade may be removed and a new blade substituted in lieu thereof.

In Figures 6 and 7 of the drawings, we have illustrated a slight modification of the

invention. In this modification, the blade is indicated at 19, the sections of the head at 20, the jaws of said sections at 21, and the collar at 22. Extending transversely 5 through the jaws 21 and through the upper end of the blade 19 is a medially disposed locking pin 23, the jaws being counterbored at their inner sides to accommodate said pin so that the pin will thus be held against 10 longitudinal movement and formed at the end portions of the pin are studs 24 projecting through the jaws. Threaded upon these studs are nuts 25 accommodated in suitable recesses in the outer faces of the 5 jaws. Thus, these nuts may be adjusted for binding the jaws against the blade in addition to the clamping action exerted by the collar 22 while the pin will also serve to provide a rigid connection between the 20 blade and the head. Formed through the sections 20 to straddle the locking pin 23 are water passages 26 which, due to the presence of said pin, are inclined upwardly, the lower ends of said passages being staggered with 25 respect to each other while the upper ends of the passages lie in the same plane. Otherwise, this modification is identical with the preferred construction.

In Figure 8 of the drawings, we have 30 illustrated a still further modification of the invention. In this modification, the blade is indicated at 27, the head at 28, and the

collar at 29. In the present instance, a pair of spaced locking pins 30 are employed, these locking pins being identical with the 35 locking pins 23 of the prior modification and extending through the upper end of the blade and the jaws of the head binding said jaws against the blade. Formed through the sections of the head between said pins are water passages 31 similar to the passages 17. Otherwise, this modification is identical with the preferred construction and further description is accordingly believed unnecessary. 40

Having thus described the invention, what is claimed as new is:

A drill of the character described including a head comprising mating sections, a blade clamped between the sections of the head, a locking pin extending through the blade forming a rigid connection between the blade and head and provided at the ends thereof with reduced studs projecting through said sections and defining shoulders to coact with the sections centering the pin upon the head as well as limiting the pin against endwise movement, and securing nuts carried by the outer ends of said studs securing the sections in mating relation. 45

In testimony whereof we affix our signatures.

ORVILLE E. MURPHY. [L. S.]
SEBERN W. GRAHAM. [L. S.]
